UNITED STATES PATENT OFFICE.

DANIEL S. HAGER, OF TOLEDO, OHIO.

PNEUMATIC-TUBE CASH-CARRIER.

No. 886,496.

Specification of Letters Patent.

Patented May 5, 1908.

Application filed June 1, 1907. Serial No. 376,762.

To all whom it may concern:

Be it known that I, DANIEL S. HAGER, a citizen of the United States of America, residing at Toledo, in the county of Lucas and State of Ohio, have invented certain new and useful Improvements in Pneumatic-Tube Cash-Carriers, of which the following is a specification, reference being had therein to the accompanying drawings.

10 In pneumatic cash carrier systems in which the cash cups or carriers proper, usually metal cylinders, are forced through conduits by air, it is customary to secure felt washers or plugs to the ends of the carriers, for the double purpose of acting as a packing ring, and as a buffer when the carrier encounters a stop. These washers wear rapidly and have to be replaced frequently. Further, because of the shocks and rough usage to which they 20 are subjected, they frequently become detached.

15 This invention relates to means for securing the felt plugs in place, so that they cannot work loose, while at the same time, they may 25 be readily replaced.

The invention consists in the matters hereinafter set forth, and more particularly pointed out in the appended claims.

Referring to the drawings, Figure 1 is a 30 view in side elevation, partially in section, of a cash carrier provided with felt ends or washers, secured to the shell by fastening means embodying the features of the invention. Fig. 2 is a view in detail of an anchor 35 plate. Fig. 3 is an end view of Fig. 1 with the felt filling disk removed.

In the drawings, 1 represents a felt washer or plug of the usual rounded exterior, slightly larger than the head 2 of a cylindrical cash 40 carrier 3. This plug is centrally counterbored and apertured for a screw or bolt 4, which passes through the cylinder head 2 and is provided with a metal washer 5, seated at the bottom of the counterbore, and a bur or 45 nut 6 bearing against the washer in the usual manner. To lock these parts against displacement, an anchor plate is used. In the preferred form of construction, this is formed up of one piece of sheet metal, and is a centrally apertured disk 7 secured against the inner face of the cylinder head 2 by the bolt 50 head 8, having two or more arms 9, in the form of narrow strips, which pass through suitably arranged slots in the cylinder head, 55 mating apertures 10 in the felt plug, and registering holes 11 in the metal washer 5. The

outer or projecting end portions 12 of these arms are bent down flat against the outer face of the washer, and turned against the facets 13 of the bolt nut 6. Thus the nut of 60 the clamping bolt is locked against rotation and cannot work loose. The washer against which the nut bears, is also held from turning and cannot move or creep on the felt. The felt plug is kept from turning on the cylinder and the repeated compression and expansion of the felt cannot affect or move the washer or nut, and the metal parts are shielded from contact with the wall or stops of the conduits. At the same time by removing 70 the filling disk 14 of felt which is forced into the outer end of the counterbore of the plug to close the same, the arms may be straightened out, the nut turned off, and the metal washer and felt slipped off and a new plug 75 put on and secured as before.

Obviously, the details of construction may be varied without departing from the spirit of my invention, and I do not care to limit myself to any particular form or arrangement 80 of parts.

I claim as my invention:—

1. The combination with a carrier cylinder and felt plug thereon of a bolt, bolt nut, and washer securing the plug to the cylinder and means secured to the cylinder head by the bolt and extended through the plug and washer adapted to anchor the plug and bolt nut and washer from rotation on the head and on each other. 90

2. The combination with a carrier cylinder and felt plug thereon of a bolt, bolt nut, and washer securing the plug to the cylinder and means secured to the cylinder head by the bolt and extended through the plug and washer adapted to anchor the plug and bolt nut and washer from rotation on the head and on each other, said securing and anchoring means being shielded by the felt plug. 95

3. The combination with a carrier cylinder and a felt plug thereon, of a bolt, bolt nut, and washer securing the plug to the cylinder head, and an anchor plate consisting of a sheet metal disk between the bolt-head and cylinder, provided with arms passing through the head, plug and bolt washer, and engaging the sides of the bolt nut. 100

4. The combination with a carrier cylinder and a felt plug thereon, of a bolt centrally securing the plug to the cylinder head by a washer and nut countersunk in the felt plug, and an anchor plate consisting of a sheet 110

metal disk clamped between the cylinder head and bolt head, arms integral with the disk passing through apertures in the cylinder head, felt plug and washer, bent against the outer side of the washer and the facets of the nut.

5. The combination with a carrier cylinder and a felt plug thereon, secured together by a central bolt, and bolt nut and washer of an anchor plate having an apertured body disk of sheet metal between the bolt head and cylinder head, and parallel strips of sheet metal integral with the disk passing through aper-

tures in the cylinder head, plug and bolt washer, adapted to be bent flat against the outer side of the washer and the facets of the bolt nut, the bolt nut, washer and projecting portions of the anchor arms being countersunk deeply into the face of the plug.

In testimony whereof I affix my signature 20 in presence of two witnesses.

DANIEL S. HAGER.
